ELECTROMAGNET

Marion R. Winkler, Chicago, Ill.

Application October 10, 1940, Serial No. 360,545

8 Claims. (Cl. 175—341)

The invention relates to electromagnets and is particularly applicable to electromagnets which are to respond rapidly and which reciprocate through a relatively short distance.

An object of the invention is to provide an electromagnet which quickly responds to the energization and deenergization thereof.

Another object is to provide an electromagnet which is highly efficient when energized for short periods.

Another object is to provide an electromagnet which requires a relatively small amount of energy for establishment of a given flux therein.

Another object is to provide a short stroke magnet having a relatively high pull.

Another object is to provide an electromagnet having a small mass which must be accelerated upon its response.

Another object is to provide an electromagnet which has a relatively low inductance.

Other objects and advantages will hereinafter appear.

The accompanying drawing is illustrative of an embodiment of the invention.

In the drawing

Fig. 1 is a side view of the electromagnetic frame embodying the invention.

Figs. 2 and 3 show somewhat diagrammatically different positions of the movable armature of the electromagnet relatively to the stationary polar member, the lower part of each figure representing one-half of the width of the stationary polar member, while the upper part represents one-half of the width of the armature or movable polar member, both in a plane parallel to the laminations.

Fig. 4 is a cross section through a magnet along the lines 4—4 of Fig. 1, while

Fig. 5 is a detail showing of the flux distribution for a given position of the movable polar member or plunger.

Figs. 6 and 7 are fragmentary cross sections along the lines 6—6 and 7—7, respectively, of Fig. 2.

Referring to the drawing the electromagnet which is of the solenoid type comprises a core, shown more in detail in Figs. 4, 6 and 7, consisting of a number of spaced laminated non-magnetic strips or units 5 which are rigidly attached to a top member 2, comprising a multiplicity of magnetizable laminations 2a and 2b, respectively, of a magnet frame or yoke. The elements 5 of said core extend axially between the top member 2 and a bottom member 3 of said yoke. The bottom member 3 comprises a multiplicity of

magnetizable laminations 3a and 3b, respectively. The strips 5 are interleaved with the laminations of the top member 2, as shown in Fig. 6, and are fastened thereto by means of rivets 6. The magnet yoke is arranged symmetrically with respect to the core, and the top and bottom members thereof are joined by side members 4—4, which are also composed of laminations of magnetic material.

10 Rectangular openings 7 are cut out of the strips 5 at equal distances from each other along the entire length of said strips, the distance between the individual openings being somewhat less than the axial width of the openings. The openings 7 have magnetic inserts 7a equal in thickness to that of the respective strip, so that the strips 5 present a smooth sliding surface.

The magnet is provided with a reciprocable plunger comprising a plurality of spaced non-magnetic strips or units 8, which are also arranged in parallel relationship to each other and alternating with the strips 5, and may slide longitudinally relatively to the latter. The strips 8 are joined together at their lower ends by means of rivets 9, a plurality of plates 8a and a pair of plates 8b being interposed therebetween as shown, so as to provide a space between the strips 8, to permit them to pass between the spaced strips 5, and to provide means for attachment of a load. The strips 8 are provided with openings 10, which are of a size and spacing substantially the same as that of the openings 7 of the stationary strips 5, said openings 10 having magnetic inserts 10a of the aforementioned character.

The central core, comprising the stationary strips 5 and the slidable armature comprising the strips 8, is surrounded by an energizing coil 4 in the usual manner. The laminations of the respective side members 4, and of the top and bottom members 2a and 2b, and 3a and 3b have their intermediate portions rigidly connected by rivets 11, whereas the overlapped ends of the respective members are joined by rivets 12, at the corners of said yoke, thus providing a rigid frame.

It will be noted from Fig. 6 that the laminations 2a are arranged so that they abut the side edges of the strips 5, while the laminations 2b extend through the central portion of the member 2 to provide for the proper spacing of the strips 5. Similarly the laminations 3a are of such length that they abut the side edges of the movable strips 8, while the laminations 3b extend across the center of the member 3 to pro-

vide, in combination with the alternate members 3a, openings for the passage of the strips 8.

The approximate path of the magnetic flux between the inserts 1a of the central core strips 5 and the inserts 10a of the plunger strips 8 have been indicated by the lines f of the fragmentary diagram Fig. 5, while the paths of the lines of force through the entire central part of the electromagnet are also indicated diagrammatically by the curved lines f in Figs. 2, 3 and 4.

From this it will be seen that the air gaps of the magnetic field of the core are connected in series, while the pull exerted by the magnetic flux on the various magnetizable elements of the movable core acts in parallel, that is the total pull on the armature is the sum of the pulls between the individual magnetic elements. As a result the magnet is capable of exerting on the movable armature a pull which for a given mass of magnetic material and for a given excitation is greatly in excess of that obtained by a conventional magnet. Thus a magnet with an effective cross sectional area of approximately $\frac{1}{8}$ square inch exerts a force of 50 pounds over a maximum distance of $\frac{5}{64}$ of an inch, while the actual weight of the plunger is approximately 2 ounces. It is thus apparent that a magnet in accordance with the present design yields for a given weight and a given excitation a pull which over short distances is much greater than that of magnets of conventional design. Furthermore in view of the fact that the magnetic mass which has to be energized to produce the magnetic field and the resultant pull is relatively small, the time constant of such magnet is also reduced, so that the magnet responds very quickly upon the closure of the energizing circuit, with the further result that the efficiency of the magnet in performing a certain amount of work is relatively high.

While the foregoing description and the drawings show a solenoid type of reciprocating magnet it is obvious that the principle of the design may also be adapted to other mechanical devices in which for instance the armature has an angular rather than a reciprocating motion relative to the stationary pole. Other modifications will be obvious to those skilled in the art.

What I claim as new and desire to secure by Letters Patent is:

1. An electromagnet comprising two cooperative elongated polar members movable relatively in the direction of their major axis, and a magnetizing winding adapted to induce a magnetic flux in the direction of said axis, each of said members comprising a plurality of substantially similar units spaced apart from each other transversely to said axis and the units of one member alternating with the units of the other member, each unit comprising a non-magnetic solid support and a plurality of similar magnetic elements attached to said support and spaced from each other in the direction of said axis.

2. An electromagnet comprising a magnetizable frame, a winding adapted to induce in said frame a magnetic flux terminating in spaced magnetic poles of opposite polarity, two cooperative elongated polar members movable relatively in the direction of their major axis and arranged with their major axis between said poles of opposite polarity, each of said members comprising a plurality of substantially similar units spaced apart from each other transversely to said axis and the units of one member alternating with the units of the other member, each unit comprising a non-magnetic solid support and a plurality of similar magnetic elements attached to said support and spaced from each other in the direction of said axis.

similar magnetic elements attached to said support and spaced from each other in the direction of said axis.

3. An electromagnet comprising an energizing winding, two cooperative members arranged with their major axis in the direction of the magnetic field induced by said winding and movable relatively in the direction of said axis, each of said members comprising a plurality of substantially similar units spaced apart from each other transversely to said axis, and the units of one member alternating with the units of the other member, each unit comprising a non-magnetic solid support and a plurality of similar magnetic elements attached to said support and spaced from each other in the direction of said axis.

4. A short stroke electromagnet having a relatively high pull, comprising an energizing winding, a frame composed of magnetic material associated with said winding to provide a path for the magnetic flux induced by the latter, two cooperative polar members associated with said frame, one of said polar members being fixed to said frame and the other polar member being movable relatively to said frame and said first polar member, each of said polar members being composed of a plurality of spaced parallel strips, each of said strips being composed of non-magnetic material and each carrying a plurality of like elements of magnetic material fixedly spaced apart from each other in the direction of the length of the strip, and the strips of the two polar members being interleaved, whereby the strips of the movable polar member are relatively movable in the spaces between the strips of said fixed polar member.

5. A short stroke electromagnet having a relatively high pull, comprising an energizing winding, a frame composed of magnetic material associated with said winding to provide a path for the magnetic flux induced by the latter, two cooperative polar members associated with said frame, one of said polar members being fixed to said frame and the other polar member being movable relatively to said frame and said first polar member, each of said polar members being composed of a plurality of spaced parallel strips, each of said strips being composed of non-magnetic material and each carrying a plurality of like elements of magnetic material fixedly spaced apart from each other in the direction of the length of the strip, the strips of the two polar members being interleaved, whereby the strips of the movable polar member are relatively movable in the spaces between the strips of said fixed polar member, and the distance between the respective elements of each strip being less than the dimensions of each element axially of said winding, for the purpose set forth.

6. An electromagnet comprising an energizing winding, two cooperative polar members arranged with their major axis in the direction of the magnetic field induced by said winding and movable relatively in the direction of said axis, a magnetizable frame arranged to complete the magnetic circuit for the flux induced in said polar members, each of said members comprising a plurality of substantially similar units spaced apart from each other transversely to said axis and the units of one member alternating with the units of the other member, each unit comprising a non-magnetic solid support and a plurality of similar magnetic elements attached to said support and spaced from each other in the direction of said axis.

said support and spaced from each other in the direction of said axis.

7. An electromagnet comprising a magnetizable frame, a winding adapted to induce in said frame a magnetic flux, said frame terminating in spaced magnetic poles of opposite polarity, two cooperative elongated polar members movable relatively in the direction of their major axis and arranged with their major axis between said poles of opposite polarity, each polar member being composed of a plurality of spaced flat parallel strips each comprising a non-magnetic frame and a plurality of magnetizable elements fixedly spaced apart from each other in the direction of said axis, and strips of the two polar members being interleaved, whereby the strips of each are relatively movable in the spaces between the strips of the other.

8. An electromagnet comprising an energizing winding, two cooperative polar members surrounded by said winding, a magnetizable frame surrounding said winding and forming a return path for the magnetic flux induced thereby, one of said polar members being fixed to said frame and the other polar member being movable rectilinearly relatively to said frame and said first polar member, each polar member being composed of a plurality of spaced flat parallel strips each comprising a non-magnetic frame and a plurality of magnetizable inserts fixedly spaced apart from each other in the direction of the axis of the winding, and the strips of the two polar members being interleaved, whereby the strips of each are relatively movable in the spaces between the strips of the other.
